UNITED STATES PATENT OFFICE.

WILLIAM J. KNOLL, OF CHICAGO, ILLINOIS, ASSIGNOR TO H. B. ROUSE & COMPANY, OF CHICAGO, ILLINOIS, A CORPORATION OF ILLINOIS.

PRINTING-PLATE HOLDER.

No. 913,736.

Specification of Letters Patent.

Patented March 2, 1909.

Application filed November 4, 1908. Serial No. 461,097.

To all whom it may concern:

Be it known that I, WILLIAM J. KNOLL, citizen of the United States, residing at Chicago, in the county of Cook and State of Illinois, have invented a certain new and useful Improvement in Printing-Plate Holders, of which the following is a full, clear, concise, and exact description, reference being had to the accompanying drawings, 10 forming a part of this specification.

My invention relates to that class of printing plate holders which employ traveling jaws and gearing for effecting the travel of the jaws and preferably accessible through 15 apertures formed in the jaws transversely to the line of jaw travel. The advantages of such printing plate holders are too well known to those skilled in the art to require recital, this being particularly the case with 20 structures in which the jaws are provided with apertures that extend transversely to the line of jaw travel.

It is the object of my invention to simplify the construction of such printing plate 25 holders and to produce a printing plate holder of the class described which will be more durable and more effective in operation than those which have hitherto been employed in practice.

30 My invention, in one embodiment, may be generally described as a printing plate holder which includes a traveling plate-holding jaw, a threaded element extending substantially parallel with the direction of travel of the jaw, a rotatable element in engagement with the threaded element, whereby the rotatable element is caused to advance or recede, according to the direction of rotation of the rotatable element, in directions 35 substantially parallel with the threaded element; said plate-holding jaw and rotatable element having engagement which permits the rotatable element to turn with respect to the jaw, but forces the jaw to move back and forth as the rotatable element moves back and forth, said jaw being apertured 45 transversely to the line of travel of the jaw to permit of the application of operating force therethrough to the rotatable element.

50 The preferred embodiment of my invention may be generally described as comprising a printing plate holder which includes a traveling plate-holding jaw, a threaded element extending substantially parallel with 55 the direction of travel of the jaw, a rotatable

element in engagement with the threaded element and co-axial therewith, whereby the rotatable element is caused to advance or recede, according to the direction of rotation of the rotatable element, in directions substantially parallel with the threaded element, 60 said plate-holding jaw and rotatable element having engagement which permits the rotatable element to turn with respect to the jaw, but forces the jaw to move back and forth as the rotatable element moves back and forth, said jaw being apertured transversely to the line of travel of the jaw to permit of the application of operating force therethrough to the rotatable element, a gear 65 wheel carried by the rotatable element and co-axial therewith, a second gear wheel in mesh with the first and carried by the jaw and accessible to an operating tool insertible through the aperture in the jaw, the axis of 70 the second gear wheel being in alinement with the aperture in the jaw that is transverse to the direction of travel of the jaw, and a block adapted to be inserted in a plate 75 foundation and carrying said threaded element and also supporting the traveling jaw in its travel.

The rotatable element may be provided with a bore in threaded engagement with a stationary threaded shaft or it may be in the 80 form of a head fixed upon a rotatable and longitudinally movable threaded shaft or the rotatable element may have its periphery in threaded engagement with threads within the barrel-like recess in the block structure. 85 While I prefer to employ an aperture formed in the jaw and extending transversely to the line of travel, I do not wish to be limited to this embodiment of my invention.

I will explain my invention more fully by 90 reference to the accompanying drawing, in which—

Figure 1 is an end view of a device made in accordance with one embodiment of the invention. Fig. 2 is a sectional view on line 2 2 of Fig. 1. Fig. 3 is a sectional view on line 3 3 of Fig. 2. Fig. 4 is a bottom view of the traveling jaw structure. Fig. 5 is a sectional view on line 5 5 of Fig. 2. Fig. 6 is a view of another embodiment of the invention in which the rotatable element is in fixed relation with a threaded shaft which is in threaded engagement with a portion of the block structure and is adapted to move back and forth with relation thereto as the 105 110

threaded shaft is turned in one direction or the other. Fig. 7 is a longitudinal sectional view illustrating another embodiment of the invention having a threaded barrel portion 5 in a block structure engaging a peripherally threaded rotatable element.

Like parts are indicated by similar characters of reference throughout the different figures.

10 In each of the embodiments of my invention, I have shown a block *a* having a barrel-like recess *b* which is open at the top of the block to permit of the mechanical interrelation of parts within the barrel-like recess 15 and parts above the barrel-like recess, irrespective of the positions which the traveling jaw structure, hereinafter to be described, may occupy. The block *a* is, as has been stated, provided with an opening at its top portion 20 that permits of mechanical inter-relation of parts within the barrel-like recess *b* and parts outside of said barrel-like recess, the longitudinal margins of this opening being provided with grooves *c* which receive tongues *d* 25 projecting laterally from the base *e* of the jaw, thereby to confine the jaw in its proper travel and to hold it in proper relation to the block. The jaw portion *f* which is directly to engage the plate, is carried upon the jaw base 30 *e* and is shown as being in pivotal relation therewith, but to which relationship I do not wish to be limited. The portion *f* of the jaw structure overlies the block structure *a*, the upper surface of the base *e* being desirably, 35 though not necessarily, flush with the upper surface of the block. The jaw base *e* is provided with a downwardly extending projection *g* which has such engagement with the rotating wheel or element *h* as will permit said 40 element to rotate without having any rotating effort exerted upon the jaw base, but which engagement will force the movement of said projection together with the parts that are mechanically connected therewith in a 45 straight line of travel parallel with the straight line movement of said rotating wheel. While I prefer the employment of the projection *g* for the purpose of maintaining the engagement prescribed with the 50 wheel *h*, I do not wish to be limited thereto. Where the projection *g* is employed, it is caused to enter a peripheral recess *i* in the wheel *h*, so that the traveling jaw structure is bound to move forward or back, according 55 to the forward or back movement of said wheel. The rotating element *h* is in threaded engagement with some threaded portion that extends substantially parallel with the direction of travel of the jaw, and, in order 60 that this rotating wheel or element *h* may be operated to the best advantage, I provide an aperture *f'* in the jaw which is perpendicular with respect to the axis of the rotating element *h*, whereby the application of operating force through the jaw to the rotating ele-

ment *h* is permitted. In the preferred embodiment of the invention, I form a gear wheel *l* preferably integral with the wheel *h* and, therefore, having an axis coincident with the axis of said wheel *h* and coincident with the threaded portion of the structure that is in threaded engagement with said wheel *h*. A second gear wheel *m* which is provided beneath the jaw base *e*, is journaled upon said jaw base, the axis of the wheel *m* being in 75 alinement with the aperture *f'* in the jaw. The hub of the gear wheel *m* is provided with an aperture having angularly related walls and is located in alinement with the aperture *f'*, whereby the end of an operating tool *o* 80 (Fig. 6) shaped correspondingly to the aperture in the wheel *m*, may, upon being inserted in said aperture and thereafter turned, effect a rotation of the gear wheel *m*, and thereby the rotation of the gear wheel *l*, 85 which being fixed with respect to the rotating element *h*, causes said element *h* to rotate, which element, by reason of its threaded connection, is thereby forced to move backwardly or forwardly, according to the 90 direction of its rotation, whereby, through the intermediation of the projection *g*, the jaw structure is forced to travel, the jaw structure in its travel carrying with it the gear wheel *m*, so that irrespective of the 95 position of the traveling jaw, the gearing described is always in position to be operated by the tool inserted through the jaw to effect the travel of the jaw as desired.

In the embodiment of the invention shown, 100 the aperture *f'* is partially filled by a tubular extension of the hub of the wheel *m*, the bore of said tubular extension permitting the passage of the operating tool through the jaw and into operative engagement with the gear 105 wheel *m*.

The specific description so far given embraces all of the embodiments of the invention illustrated. I will now describe the particulars in which the various embodiments 110 differ.

In Figs. 1 to 5, inclusive, the rotating wheel or element *h* is in the form of a nut having a threaded bore in threaded engagement with a normally stationary threaded 115 shaft *k*. In Fig. 6 the rotatable element is in fixed relation with a threaded shaft *q* which is in threaded engagement with an end wall portion of the block structure and is adapted to move back and forth with relation thereto as the threaded shaft is turned in one direction or the other by the turning movement imparted to it by the wheel *l*, the bodily movement of the rotating threaded shaft in one direction or the other 120 effecting corresponding movement of the jaw. In Fig. 7 I have shown a structure wherein the barrel portion is provided with threads *r* which engage the peripherally threaded rotatable element *h*, thereby to 125 130

force the travel of the jaw upon rotation of the wheel h . In all embodiments of the invention that I have illustrated, the axis of the portion of the structure in threaded engagement with the wheel h is parallel with the line of travel of the jaw and said axis is coincident with the axes of the elements h and the gear wheel l , while the axis of the wheel m , which, as stated, is in alignment 10 with the aperture f^1 , is transverse to the axis of the threaded portion in engagement with the wheel h , the axis of the wheel m and said aperture f^1 being desirably perpendicular to the axis of the threaded portion in engagement 15 with the element h . In all of the illustrated embodiments of my invention, the only function of the gearing l and m is to effect the rotation of the element h , the purchase of the jaw being had upon the shaft k , 20 the shaft q or the threads r , as the case may be, without the intervention of the gearing l and m . The gear wheels l and m are desirably miter gear wheels, but I do not wish to be limited to miter gear wheels. 25 By way of a general summation, it may be stated that my invention here disclosed includes a traveling plate-holding jaw, a gear element (which is the shaft or threaded bore, in the embodiments of the invention illustrated), a jaw-actuating element (such as the wheel h) in engagement with said gear element and the plate-holding jaw, whereby as the jaw-actuating element is moved with respect to said gear element, the plate-holding 30 jaw is caused to advance or recede, a second gear element (one of the bevel gear wheels, in the embodiments of the invention illustrated) moving with the jaw-actuating element, and a third gear element (the other of the bevel gear wheels) in engagement with the second gear element and moving with the jaw and adapted to be operated by an operating tool, the plate-holding 35 jaw having purchase upon the first gear element independently of the other gear elements by reason of the engagement of the jaw actuating element with the first gear element.

While I have herein shown and particularly described the preferred embodiments of my invention, I do not wish to be limited to the precise constructions illustrated, as changes may be made without departing from the spirit of the invention.

Having thus described my invention, I claim as new and desire to secure by Letters Patent the following:—

1. A printing plate holder including a traveling plate-holding jaw, a threaded element extending substantially parallel with the direction of travel of the jaw, a rotatable element in engagement with the threaded element, whereby the rotatable element is caused to advance or recede, according to 60 the direction of rotation of the rotatable element,

ment, in directions substantially parallel with the threaded element, said plate-holding jaw and rotatable element having engagement which permits the rotatable element to turn with respect to the jaw, but 70 forces the jaw to move back and forth as the rotatable element moves back and forth, a gear wheel carried by the rotatable element, and a second gear wheel in mesh with the first and moving with the jaw and accessible 75 to an operating tool, the plate-holding jaw having purchase upon the threaded element independently of the gear wheels by reason of the engagement of said rotatable element with said threaded element.

2. A printing plate holder including a traveling plate-holding jaw, a threaded element extending substantially parallel with the direction of travel of the jaw, a rotatable element in engagement with the threaded element, whereby the rotatable element is caused to advance or recede, according to the direction of rotation of the rotatable element, in directions substantially parallel 80 with the threaded element, said plate-holding jaw and rotatable element having engagement which permits the rotatable element to turn with respect to the jaw, but 85 forces the jaw to move back and forth as the rotatable element moves back and forth, a gear wheel moving with the rotatable element, and a second gear wheel in mesh with the first and moving with the jaw and accessible to an operating tool insertible through the aperture in the jaw the plate-holding jaw having purchase 90 upon the threaded element independently of 95 the gear wheels by reason of the engagement of said rotatable element with said threaded element.

3. A printing plate holder including a traveling plate-holding jaw, a threaded element extending substantially parallel with the direction of travel of the jaw, a rotatable element in engagement with the threaded element, whereby the rotatable element is caused to advance or recede, according to 100 the direction of rotation of the rotatable element, in directions substantially parallel with the threaded element, said plate-holding jaw and rotatable element having engagement which permits the rotatable element to turn with respect to the jaw, but 105 forces the jaw to move back and forth as the rotatable element moves back and forth, a gear wheel moving with the rotatable element and co-axial therewith, and a second gear wheel in mesh 110 with the first and moving with the jaw and 115

accessible to an operating tool insertible through the aperture in the jaw, the plate-holding jaw having purchase upon the threaded element independently of the gear 5 wheels by reason of the engagement of said rotatable element with said threaded element.

4. A printing plate holder including a traveling plate-holding jaw, a threaded element extending substantially parallel with 10 the direction of travel of the jaw, a rotatable element in engagement with the threaded element, whereby the rotatable element is caused to advance or recede, according to the direction of rotation of the rotatable element, 15 in directions substantially parallel with the threaded element, said plate-holding jaw and rotatable element having engagement which permits the rotatable element to turn with respect to the jaw, but forces the jaw to move 20 back and forth as the rotatable element moves back and forth, said jaw being apertured transversely to the line of travel of the jaw to permit of the application of operating force therethrough to the rotating element, 25 a gear wheel moving with the rotatable element and co-axial therewith, and a second gear wheel in mesh with the first and moving with the jaw and accessible to an operating tool insertible through the aperture in the 30 jaw, the axis of the second gear wheel being in vertical alinement with the aperture in the jaw, the plate-holding jaw having purchase upon the threaded element independently of the gear wheels by reason of the engagement 35 of said rotatable element with said threaded element.

5. A printing plate holder including a traveling plate-holding jaw, a threaded element extending substantially parallel with 40 the direction of travel of the jaw, a rotatable element in engagement with the threaded element, whereby the rotatable element is caused to advance or recede, according to the direction of rotation of the rotatable element, in 45 directions substantially parallel with the threaded element, said plate-holding jaw and rotatable element having engagement which permits the rotatable element to turn with respect to the jaw, but forces the jaw to 50 move back and forth as the rotatable element moves back and forth, said jaw being apertured transversely to the line of travel of the jaw to permit of the application of operating force therethrough to the rotating element, a gear wheel moving with the rotatable element, a second gear wheel in mesh with the first and moving with the jaw and accessible to an operating tool insertible through the aperture in the jaw, the plate-holding jaw 55 having purchase upon the threaded element independently of the gear wheels by reason of the engagement of said rotatable element with said threaded element, and a block adapted to be inserted in a plate foundation and carrying said threaded element and also supporting the traveling jaw in its travel. 60

6. A printing plate holder including a traveling plate-holding jaw, a threaded element extending substantially parallel with 65 the direction of travel of the jaw, a rotatable element in engagement with the threaded element, whereby the rotatable element is caused to advance or recede, according to the direction of rotation of the rotatable element, in 70 directions substantially parallel with the threaded element, said plate-holding jaw and rotatable element having engagement which permits the rotatable element to turn with respect to the jaw, but forces the jaw to move 75

of the engagement of said rotatable element with said threaded element.

6. A printing plate holder including a traveling plate-holding jaw, a threaded element, a rotatable element in engagement with the threaded element, whereby the rotatable element is caused to advance or recede, according to the direction of rotation of the rotatable element, said plate-holding jaw and rotatable element having engagement 80 which permits the rotatable element to turn with respect to the jaw, but forces the jaw to move back and forth as the rotatable element moves back and forth, a gear wheel moving with the rotatable element, 85 and a second gear wheel in mesh with the first and moving with the jaw and accessible to an operating tool, the plate-holding jaw having purchase upon the threaded element independently of the gear wheels by reason 90 of the engagement of said rotatable element with said threaded element.

7. A printing plate holder including a traveling plate-holding jaw, a threaded element extending substantially parallel with 95 the direction of travel of the jaw, a rotatable element in engagement with the threaded element, whereby the rotatable element is caused to advance or recede, according to the direction of rotation of the rotatable element, in 100 directions substantially parallel with the threaded element, said plate-holding jaw and rotatable element having engagement which permits the rotatable element to turn with respect to the jaw, but forces the jaw to move back and forth as the rotatable element 105 moves back and forth, said jaw being apertured transversely to the line of travel of the jaw to permit of the application of operating force therethrough to the rotating element, a gear wheel moving with the rotatable element, a second gear wheel in mesh with the first and moving with the jaw and accessible to an operating tool insertible through the aperture in the jaw, the plate-holding jaw 110 having purchase upon the threaded element independently of the gear wheels by reason of the engagement of said rotatable element with said threaded element, and a block adapted to be inserted in a plate foundation 115 and carrying said threaded element and also supporting the traveling jaw in its travel.

8. A printing plate holder including a traveling plate-holding jaw, a threaded element extending substantially parallel with 120 the direction of travel of the jaw, a rotatable element in engagement with the threaded element, whereby the rotatable element is caused to advance or recede, according to the direction of rotation of the rotatable element, in 125 directions substantially parallel with the threaded element, said plate-holding jaw and rotatable element having engagement which permits the rotatable element to turn with respect to the jaw, but forces the jaw to move 130

back and forth as the rotatable element moves back and forth, said jaw being apertured transversely to the line of travel of the jaw to permit of the application of operating force therethrough to the rotatable element, a gear wheel moving with the rotatable element and co-axial therewith, a second gear wheel in mesh with the first and moving with the jaw and accessible to an operating tool insertible through the aperture in the jaw, the plate-holding jaw having purchase upon the threaded element independently of the gear wheels by reason of the engagement of said rotatable element with said threaded element, and a block adapted to be inserted in a plate foundation and carrying said threaded element and also supporting the traveling jaw in its travel.

9. A printing plate holder including a traveling plate-holding jaw, a threaded element extending substantially parallel with the direction of travel of the jaw, a rotatable element in engagement with the threaded element, whereby the rotatable element is caused to advance or recede, according to the direction of rotation of the rotatable element, in directions substantially parallel with the threaded element, said plate-holding jaw and rotatable element having engagement which permits the rotatable element to turn with respect to the jaw, but forces the jaw to move back and forth as the rotatable element moves back and forth, said jaw being apertured transversely to the line of travel of the jaw to permit of the application of operating force therethrough to the rotatable element, a gear wheel moving with the rotatable element and co-axial therewith, a second gear wheel in mesh with the first and moving with the jaw and accessible to an operating tool insertible through the aperture in the jaw, the axis of the second gear wheel being in vertical alinement with the aperture in the jaw, the plate-holding jaw having purchase upon the threaded element independently of the gear wheels by reason of the engagement of said rotatable element with said threaded element, and a block adapted to be inserted in a plate foundation and carrying said threaded element and also supporting the traveling jaw in its travel.

10. A printing plate holder including a traveling plate-holding jaw, a threaded element extending substantially parallel with the direction of travel of the jaw, a rotatable element in engagement with the threaded element, whereby the rotatable element is caused to advance or recede, according to the direction of rotation of the rotatable element, in directions substantially parallel with the threaded element, said plate-holding jaw and rotatable element having engagement which permits the rotatable element to turn with respect to the jaw, but forces the jaw to move back and forth as the rotatable element

moves back and forth, said jaw being apertured transversely to the line of travel of the jaw to permit of the application of operating force therethrough to the rotatable element, a gear wheel moving with the rotatable element and co-axial therewith, a second gear wheel in mesh with the first and moving with the jaw and accessible to an operating tool insertible through the aperture in the jaw, the axis of the second gear wheel being in vertical alinement with the aperture in the jaw that is transverse to the direction of travel of the jaw, the plate-holding jaw having purchase upon the threaded element independently of the gear wheels by reason of the engagement of said rotatable element with said threaded element, and a block adapted to be inserted in a plate foundation and carrying said threaded element and also supporting the traveling jaw in its travel.

11. A printing plate holder including a traveling plate-holding jaw, a threaded element extending substantially parallel with the direction of travel of the jaw, a rotatable element in engagement with the threaded element, whereby the rotatable element is caused to advance or recede, according to the direction of rotation of the rotatable element, in directions substantially parallel with the threaded element, said plate-holding jaw and rotatable element having engagement which permits the rotatable element to turn with respect to the jaw, but forces the jaw to move back and forth as the rotatable element moves back and forth, said jaw being apertured transversely to the line of travel of the jaw to permit of the application of operating force therethrough to the rotatable element, a gear wheel moving with the rotatable element and co-axial therewith and with the threaded element, and a second gear wheel in mesh with the first and moving with the jaw and accessible to an operating tool insertible through the aperture in the jaw the plate-holding jaw having purchase upon the threaded element independently of the gear wheels by reason of the engagement of said rotatable element with said threaded element.

12. A printing plate holder including a traveling plate-holding jaw, a threaded element extending substantially parallel with the direction of travel of the jaw, a rotatable element in engagement with the threaded element, whereby the rotatable element is caused to advance or recede, according to the direction of rotation of the rotatable element, in directions substantially parallel with the threaded element, said plate-holding jaw and rotatable element having engagement which permits the rotatable element to turn with respect to the jaw, but forces the jaw to move back and forth as the rotatable element moves back and forth, said jaw being apertured transversely to the

line of travel of the jaw to permit of the application of operating force therethrough to the rotating element, a gear wheel moving with the rotatable element and co-axial therewith and with the threaded element, and a second gear wheel in mesh with the first and moving with the jaw and accessible to an operating tool insertible through the aperture in the jaw, the axis of the second gear wheel being in vertical alinement with the aperture in the jaw the plate-holding jaw having purchase upon the threaded element independently of the gear wheels by reason of the engagement of said rotatable element 10 with said threaded element.

13. A printing plate holder including a traveling plate-holding jaw, a threaded element extending substantially parallel with the direction of travel of the jaw, a rotatable element in engagement with the threaded element, whereby the rotatable element is caused to advance or recede, according to the direction of rotation of the rotatable element, in directions substantially parallel with the threaded element, said plate-holding jaw and rotatable element having engagement which permits the rotatable element to turn with respect to the jaw, but forces the jaw to move back and forth as the rotatable element moves back and forth, said jaw being apertured transversely to the line of travel of the jaw to permit of the application of operating force therethrough to the rotating element, a gear wheel moving with the rotatable element and co-axial therewith and with the threaded element, and a second gear wheel in mesh with the first and moving with the jaw and accessible to an operating tool insertible through the aperture in the jaw, the axis of the second gear wheel being in alinement with the aperture in the jaw, the plate-holding jaw having purchase upon the threaded element independently of the gear wheels by reason of the engagement of said rotatable element 45 with said threaded element.

14. A printing plate holder including a traveling plate-holding jaw, a threaded element extending substantially parallel with the direction of travel of the jaw, a rotatable element in engagement with the threaded element, whereby the rotatable element is caused to advance or recede, according to the direction of rotation of the rotatable element, in directions substantially parallel with the threaded element, said plate-holding jaw and rotatable element having engagement which permits the rotatable element to turn with respect to the jaw, but forces the jaw to move back and forth as the rotatable element moves back and forth, said jaw being apertured transversely to the line of travel of the jaw to permit of the application of operating force therethrough 60 to the rotating element, a gear wheel moving

with the rotatable element and co-axial therewith and with the threaded element, a second gear wheel in mesh with the first and moving with the jaw and accessible to an operating tool insertible through the aperture in the jaw, the plate-holding jaw having purchase upon the threaded element independently of the gear wheels by reason of the engagement of said rotatable element with said threaded element, and a block 70 adapted to be inserted in a plate foundation and carrying said threaded element and also supporting the traveling jaw in its travel.

15. A printing plate holder including a traveling plate-holding jaw, a threaded element extending substantially parallel with the direction of travel of the jaw, a rotatable element in engagement with the threaded element, whereby the rotatable element is caused to advance or recede, according to the direction of rotation of the rotatable element, in directions substantially parallel with the threaded element, said plate-holding jaw and rotatable element having engagement which permits the rotatable element to turn with respect to the jaw, but forces the jaw to move back and forth as the rotatable element moves back and forth, said jaw being apertured transversely to the line of travel of the jaw to permit of the application of operating force therethrough to the rotating element, a gear wheel moving with the rotatable element and co-axial therewith and with the threaded element, a second gear wheel in mesh with the first and moving with the jaw and accessible to an operating tool insertible through the aperture in the jaw, the axis of the second gear wheel being in vertical alinement with the aperture in the jaw, the plate-holding jaw having purchase upon the threaded element independently of the gear wheels by reason of the engagement of said rotatable element with said threaded element, and a block 90 adapted to be inserted in a plate foundation and carrying said threaded element and also supporting the traveling jaw in its travel.

16. A printing plate holder including a traveling plate-holding jaw, a threaded element extending substantially parallel with the direction of travel of the jaw, a rotatable element in engagement with the threaded element, whereby the rotatable element is caused to advance or recede, according to the direction of rotation of the rotatable element, in directions substantially parallel with the threaded element, said plate-holding jaw and rotatable element having engagement which permits the rotatable element to turn with respect to the jaw, but forces the jaw to move back and forth as the rotatable element moves back and forth, said jaw being apertured transversely to the line of travel of the jaw to permit of the 110

application of operating force therethrough to the rotating element, a gear wheel moving with the rotatable element and co-axial therewith and with the threaded element, a 5 second gear wheel in mesh with the first and moving with the jaw and accessible to an operating tool insertible through the aperture in the jaw, the axis of the second gear wheel being in alinement with the aperture 10 in the jaw that is transverse to the direction of travel of the jaw, the plate-holding jaw having purchase upon the threaded element independently of the gear wheels by reason of the engagement of said rotatable element 15 with said threaded element, and a block adapted to be inserted in a plate foundation and carrying said threaded element and also supporting the traveling jaw in its travel.

17. A printing plate holder including a 20 traveling plate-holding jaw, an element extending substantially parallel with the direction of travel of the jaw, a rotatable element in engagement with the first-named element, whereby the rotatable element is caused to advance or recede, according to the 25 direction of rotation of the rotatable element, in directions substantially parallel with the first-named element, said plate-holding jaw and rotatable element having engagement which 30 permits the rotatable element to turn with respect to the jaw, but forces the jaw to move back and forth as the rotatable element moves back and forth, a gear wheel moving with the rotatable element, and a 35 second gear wheel in mesh with the first and moving with the jaw and accessible to an operating tool, the plate-holding jaw having purchase upon the first-named element independently of the gear wheels by reason of the 40 engagement of said rotatable element with said first-named element.

18. A printing plate holder including a traveling plate-holding jaw, a threaded element extending substantially parallel with 45 the direction of travel of the jaw, a rotatable element in engagement with the threaded element, whereby the rotatable element is caused to advance or recede, according to the direction of rotation of the rotatable element, 50 in directions substantially parallel with the threaded element, said plate-holding jaw and rotatable element having engagement which permits the rotatable element to turn with respect to the jaw, but forces the jaw to move back and forth as the rotatable element moves back and forth, said jaw being 55 apertured transversely to the line of travel of the jaw to permit of the application of operating force therethrough to the rotatable element, a gear wheel moving with the rotatable element, and a second gear wheel in mesh with the first and moving 60 with the jaw and accessible to an operating tool, the plate-holding jaw having purchase upon the first-named element independently of the gear wheels by reason of the engagement of said rotatable element with said first-named element.

65 the second gear wheel being in vertical alinement with the aperture in the jaw, the plate-holding jaw having purchase upon the threaded element independently of the gear wheels by reason of the engagement of said rotatable element with said threaded element.

ment with the aperture in the jaw, the plate-holding jaw having purchase upon the threaded element independently of the gear wheels by reason of the engagement of said rotatable element with said threaded ele- 70

19. A printing plate holder including a traveling plate-holding jaw, a threaded element extending substantially parallel with the direction of travel of the jaw, a rotatable 75 element in engagement with the threaded element, whereby the rotatable element is caused to advance or recede, according to the direction of rotation of the rotatable element, in directions substantially parallel with the 80 threaded element, said plate-holding jaw and rotatable element having engagement which permits the rotatable element to turn with respect to the jaw, but forces the jaw to move back and forth as the rotatable element moves back and forth, said jaw being apertured transversely to the line of travel of the jaw to permit of the application of operating force therethrough to the rotatable 85 element, a gear wheel moving with the rotatable element, and a second gear wheel in mesh with the first and moving with the jaw and accessible to an operating tool insertible through the aperture in the jaw, the axis of the second gear wheel being in alinement with the aperture 90 in the jaw that is transverse to the direction of travel of the jaw, the plate-holding jaw having purchase upon the threaded element independently of the gear wheels by reason of the engagement of said rotatable 95 element with said threaded element.

20. A printing plate holder including a traveling plate-holding jaw, a gear element, a rotatable element in engagement with the first-named element, whereby the rotatable 105 element is caused to advance or recede, according to the direction of rotation of the rotatable element, said plate-holding jaw and rotatable element having engagement which permits the rotatable element to turn with 110 respect to the jaw, but forces the jaw to move back and forth as the rotatable element moves back and forth, a gear wheel moving with the rotatable element, and a second gear wheel in mesh with the first and moving 115 with the jaw and accessible to an operating tool, the plate-holding jaw having purchase upon the first-named element independently of the gear wheels by reason of the engagement of said rotatable element with said 120 first-named element.

21. A printing plate holder including a traveling plate-holding jaw, a threaded element extending substantially parallel with the direction of travel of the jaw, a rotatable 125 element in engagement with the threaded element, whereby the rotatable element is caused to advance or recede, according to the direction of rotation of the rotatable element, in directions substantially parallel with the 130

threaded element, said plate-holding jaw and rotatable element having engagement which permits the rotatable element to turn with respect to the jaw, but forces the jaw to move back and forth as the rotatable element moves back and forth, said jaw being apertured transversely to the line of travel of the jaw to permit of the application of operating force therethrough to the rotating element, 5 a gear wheel moving with the rotatable element, a second gear wheel in mesh with the first and moving with the jaw and accessible to an operating tool insertible through the aperture in the jaw, the axis of the second gear wheel being in vertical alinement with the aperture in the jaw, the plate-holding jaw having purchase upon the threaded element independently of the gear wheels by reason of the engagement of said rotatable 10 element with said threaded element, and a block adapted to be inserted in a plate foundation and carrying said threaded element and also supporting the traveling jaw in its travel.

25 22. A printing plate holder including a traveling plate-holding jaw, a threaded element extending substantially parallel with the direction of travel of the jaw, a rotatable element in engagement with the threaded element, whereby the rotatable element is caused to advance or recede, according to the direction of rotation of the rotatable element, in directions substantially parallel with the threaded element, said plate-holding jaw and rotatable element having engagement which permits the rotatable element to turn with respect to the jaw, but forces the jaw to move back and forth as the rotatable element moves back and forth, 30 said jaw being apertured transversely to the line of travel of the jaw to permit of the application of operating force therethrough to the rotating element, a gear wheel moving with the rotatable element, a second gear wheel in mesh with the first and moving with the jaw and accessible to an operating tool insertible through the aperture in the jaw, the axis of the second gear wheel being in alinement with the aperture in the jaw that 35 is transverse to the direction of travel of the jaw, the plate-holding jaw having purchase upon the threaded element independently of the gear wheels by reason of the engagement of said rotatable element with said threaded element, and a block adapted to be inserted in a plate foundation and carrying said threaded element and also supporting the traveling jaw in its travel.

23. A printing plate holder including a 60 traveling plate-holding jaw, a threaded element, a rotatable element in engagement and co-axial with the threaded element, whereby the rotatable element is caused to advance or recede, according to the direction 65 of rotation of the rotatable element, said

plate-holding jaw and rotatable element having engagement which permits the rotatable element to turn with respect to the jaw, but forces the jaw to move back and forth as the rotatable element moves back 70 and forth, said jaw being apertured to permit of the application of operating force therethrough to the rotating element, a gear wheel moving with the rotatable element and co-axial therewith, and a second gear 75 wheel in mesh with the first and moving with the jaw and accessible to an operating tool insertible through the aperture in the jaw, the axis of the second gear wheel being in alinement with the aperture in the jaw, the 80 plate-holding jaw having purchase upon the threaded element independently of the gear wheels by reason of the engagement of said rotatable element with said threaded element.

24. A printing plate holder including a 85 traveling plate-holding jaw, a threaded element, a rotatable element in engagement with the threaded element, whereby the rotatable element is caused to advance or recede, according to the direction of rotation 90 of the rotatable element, said plate-holding jaw and rotatable element having engagement which permits the rotatable element to turn with respect to the jaw, but forces the jaw to move back and forth as the rotatable element moves back and forth, said 95 jaw being apertured to permit of the application of operating force therethrough to the rotating element, a gear wheel moving with the rotatable element and co-axial therewith, 100 and a second gear wheel in mesh with the first and moving with the jaw and accessible to an operating tool insertible through the aperture in the jaw, the axis of the second gear wheel being in alinement with the 105 aperture in the jaw, the plate-holding jaw having purchase upon the threaded element independently of the gear wheels by reason of the engagement of said rotatable element with said threaded element.

25. A printing plate holder including a traveling plate-holding jaw, a threaded element, a rotatable element in engagement and co-axial with the threaded element, whereby the rotatable element is caused to 115 advance or recede, according to the direction of rotation of the rotatable element, said plate-holding jaw and rotatable element having engagement which permits the rotatable element to turn with respect to the jaw, but forces the jaw to move back and forth as the rotatable element moves back and forth, said 120 jaw being apertured to permit of the application of operating force therethrough to the rotating element, a gear wheel moving with the rotatable element and co-axial therewith, 125 and a second gear wheel in mesh with the first and moving with the jaw and accessible to an operating tool insertible through the aperture in the jaw, the axis of the second 130

gear wheel being in alinement with the aperture in the jaw, the plate-holding jaw having purchase upon the threaded element independently of the gear wheels by reason of the engagement of said rotatable element with said threaded element, and a block adapted to be inserted in the plate foundation and carrying said threaded element and also supporting the traveling jaw in its travel.

26. A printing plate holder including a traveling plate-holding jaw, a threaded element, a rotatable element in engagement with the threaded element, whereby the rotatable element is caused to advance or recede, according to the direction of rotation of the rotatable element, said plate-holding jaw and rotatable element having engagement which permits the rotatable element to turn with respect to the jaw, but forces the jaw to move back and forth as the rotatable element moves back and forth, said jaw being apertured to permit of the application of operating force therethrough to the rotating element, a gear wheel moving with the rotatable element and co-axial therewith, a second gear wheel in mesh with the first and moving with the jaw and accessible to an operating tool insertible through the aperture in the jaw, the axis of the second gear wheel being in alinement with the aperture in the jaw, the plate-holding jaw

having purchase upon the threaded element independently of the gear wheels by reason of the engagement of said rotatable element with said threaded element, and a block adapted to be inserted in the plate foundation and carrying said threaded element and also supporting the traveling jaw in its travel.

27. A printing plate holder including a traveling plate-holding jaw, a gear element, a jaw-actuating element in engagement with said gear element and the plate-holding jaw, whereby as the jaw-actuating element is moved with respect to said gear element, the plate-holding jaw is caused to advance or recede, a second gear element moving with the jaw-actuating element and a third gear element in engagement with the second gear element and moving with the jaw and adapted to be operated by an operating tool, the plate-holding jaw having purchase upon the first gear element independently of the other gear elements by reason of the engagement of the jaw-actuating element with the first gear element.

In witness whereof, I hereunto subscribe my name this third day of November, A. D., 1908.

WILLIAM J. KNOLL.
